PLATFORM RELEASE

Filed Sept. 20, 1926

INVENTOR.

James. H. Myre.

BY

Thomas J. Dammell
ATTORNEY.

UNITED STATES PATENT OFFICE.

JAMES H. MYRE, OF DETROIT, MICHIGAN.

PLATFORM RELEASE.

Application filed September 20, 1926. Serial No. 136,514.

My invention relates to a new and useful improvement in a platform release adapted for use on a game mechanism, one arrangement of which is commonly known as an African dip, such as is shown in my United States Patent No. 1,593,267, in which a person is seated on a swingable platform and upon the player striking the target is dropped from the platform on to a slide and thence precipitated into a tank of water. The present mechanism relates particularly to the releasing of the swingable platform, and it is my intention to embody in the present application such modifications, adaptations and variations of the invention as will permit its use on various devices where a swingable platform is used.

In the specified use of the invention, the release is effected by the closing of an electrical circuit upon a striking of the target by the player, and an electrical latch is released to permit the release of the retaining mechanism supporting the platform. In various modifications of such a release it has been discovered that the release sometimes becomes difficult and the mechanism fails to operate should the persons seated on the platform be of a weight exceeding a certain number of pounds.

The present invention has for its object the provision of a release mechanism of this class which will serve to retain the platform in readily releasable position, regardless of the weight placed upon the platform.

Another object of the invention is the provision of a mechanism of this class which will be quite durable in use, and free from difficulties arising through the various parts becoming disarranged or rendered inoperative for any reason.

Another object of the invention is the provision of a mechanism of this class whereby the retaining mechanism may be easily and quickly moved to operative position.

Another object of the invention is the provision of a device of this class which will be simple in structure, economical of manufacture and highly efficient in use.

Other objects will appear hereinafter.

The invention consists in the combination and arrangement of parts hereinafter described and claimed.

The invention will be best understood by a reference to the accompanying drawings which form a part of this specification and in which,

Fig. 1 is a vertical sectional view illustrating the invention in side elevation.

Fig. 2 is a sectional view taken on substantially line 2—2 of Fig. 1.

Fig. 3 is a sectional view taken on substantially line 3—3 of Fig. 1.

Fig. 4 is a fragmentary view similar to Fig. 1 showing the device moved to inoperative or releasing position.

In the drawings I have shown the mechanism enclosed in a housing 7 which may be mounted on a suitable support 8 having a horizontally extending portion 9 to which is hingedly connected a supporting platform 10. Hingedly connected to the under surface of the platform 10 is an arcuate retaining arm 11 having a shoulder 12 formed thereon and adapted to engage a vertically extending bar 13 which projects through a slot 14 formed in the upper wall of the housing 7 so as to prevent downwardly swinging of the platform 10. Mounted on the wall 15 of the housing rotatably is a roller 16 which is adapted to engage one edge of the bar 13, a similar roller 17 being rotatably mounted on the wall 15 and engaging the opposite edge of the bar 13 adjacent its lower end. A shaft 18 is supported on the wall 15 by outwardly projecting bolts 19 and 20, and rotatably mounted on the shaft 18 is a roller 21 which engages the outer face of the bar 13 and serves to prevent withdrawal of this bar from the wall 15 adjacent its lower end, the slot 14 retaining the bar 13 in position at its upper end.

Projecting outwardly from the wall 15 is a bolt or threaded stud 22 which projects through an enlarged opening 23 formed in a lever 24 which is pivotally connected by means of the bolt 25 to the bar 13. Connected at one end to the free end of the lever 24 is a spring 26, the other end of which is connected to a bolt 27 mounted on the wall 15 and projecting through an enlarged opening 28 formed in the lever 29 which is pivotally connected by the bolt 30 to a horizontally extending actuating lock bolt 31. The lock bolt 31 is provided at one end with a nose 32 adapted to engage behind the latch 33 which is electrically operated, the operating mechanism of the latch 33 being a well-known type and positioned in the housing 34 which is positioned in the recess 35 formed in the supporting member 8. Since this latching mechanism formed of itself no specific part of the present invention it is

not shown in detail as its structure is well-known.

Connected at one end to the opposite end of the lever 29 is a spring 35', the other end of which is connected to a bolt 36 projected through the tree 37 of a yoke forming bracket between the arms 38 and 39, in which is positioned a roller 40 rotatably mounted upon the bolt 41 which projects outwardly from the wall 15. A similar yoke 42 is provided between the arms in which is positioned a roller 43. As shown in Fig. 2 on the bolt 41 there is mounted in embracing relation a coil spring 44 and a nut 45 is threaded on the bolt 41 so that a threading of the nut 45 will adjust the tension of the spring 44, the other end of which engages against a shaft 46 slidably mounted on the bolt 41 at one end, and at its other end slidably mounted on the bolt 47, which is also positioned with a spring 48 and an adjusting nut 49, this bolt 47 projecting outwardly from the wall 15. Rotatably mounted on the shaft 46 is a roller 50 which is adapted to engage the outer surface of the lock bolt 31 so as to normally retain, in response to the pressure of the springs 44 and 48, the lock bolt 31 in engagement with the surface of the wall 15. A pin 51 is projected through the shaft 46 to prevent the movement of the roller 50 downward on the shaft 46. A similar roller 50' is mounted on a shaft 46' similarly supported in the manner of the supporting of the shaft 46, this roller 50' also engaging the surface of the lock bolt 31. Rotatably mounted on the lower end of the bar 13 is a roller 52 which engages the upper edge of the lock bolt 31 and is adapted upon movement of the lock bolt 31 into a predetermined position, for engaging in the recess or pocket 53 formed in the upper edge of the lock bolt 31.

In operation the lever 29 is moved into the position shown in Fig. 1 by means of a strain exerted on the cord 54. This movement of the lever 29 on its pivot 27 stretches the spring 35' and causes a longitudinal movement of the lock bolt 31 so as to force the roller 52 out of the pocket or recess 53 into the position shown in Fig. 1, thus forcing the bar 13 vertically upwardly so as to lie in a position to engage the shoulder 12. The movement of the bar 13 vertically upwardly causes a stretching of the spring 26. When the lock bolt 31 is moved into the position shown in Fig. 1 it engages behind the latch 33, the latch 33 serving to retain the lock bolt 31 in its position against the tension of the springs. Upon a releasing of the latch 33 through a closing of the circuit through the wires 55 and 56 which connect to the switch 57, which, in turn, connects, by means of the wires 58 and 59, to a suitable switch which may be closed at will, the lock bolt 31 is moved into the position shown in Fig. 4,

the springs 35' and 26 affecting the movement of the lock bolt 31 and the bar 13 so that the bar 13 is retracted sufficiently within the housing 7 to clear the shoulder 12 and permit the swinging of the platform 10. 70

This structure is one which permits an operation of the device through a release of the latch 33 regardless of the downward pressure which is exerted on the platform 10 so that a person of any weight may be used 75 in the game.

It is believed that the durability of the structure is apparent from the description, and it is also to be noted that the tension of the roller 50 and 50' will determine, to a certain extent, the pressure of the spring 35' required to move the lock bolt 31 horizontally. 80

While I have illustrated and described the preferred form of my invention, I do not 85 wish to limit myself to the precise form of structure shown, but desire to avail myself of such variations and modifications as may come within the scope of the appended claims. 90

Having thus described my invention what I claim as new and desire to secure by Letters Patent is:

1. A device of the class described comprising a swingably mounted platform; a supporting arm on said platform; a movable member for engaging said arm and locking said platform against swingable movement; pocket bearing means for engaging said movable member and preventing movement of the same, said movable member being adapted for moving into said pocket upon movement of said pocket bearing means into a predetermined position, said platform being released for swingable movement upon movement of said movable means into said pocket. 100

2. A device of the class described comprising a swingable platform; a supporting member on said platform; a movable member for engaging said supporting member and retaining said platform against swingable movement; movable means for engaging said movable member and retaining the same in operative position, said movable means having a pocket formed on its engaging surface; and means operable at will for moving said movable means to a predetermined position, said movable member upon movement of said movable means to said predetermined position moving into engagement in said pocket to inoperative position and releasing said platform for swingable movement. 115

3. A device of the class described comprising a swingable platform; supporting means for said platform; a movable member for engaging said supporting means for locking said platform against swingable movement in one direction; a movable means 125

for engaging said movable member for normally retaining said movable member in operative position in engagement with said supporting member, said movable means having a recess formed therein adapted for the reception of said movable member upon movement of said movable means into a predetermined position, the movement of said movable member into engagement with said recess effecting a disengagement of said movable member with said supporting member; resilient means for moving said movable means into predetermined position; and means releasable at will for resisting movement of said movable means.

4. A device of the class described comprising a swingable platform; a support for said platform; a movable member for engaging said support and preventing swingable movement of said platform; a movable means for engaging said movable member and normally retaining the same in engagement with said support, said movable means being provided with a recess for the reception of said movable member upon movement of said movable means to a predetermined position, the movement of said movable member into engagement with said recess effecting a disengagement of said movable member from said support; means for

preventing movement of said movable means into said predetermined position; and resilient means for moving said movable means into said predetermined position upon release of said preventing means. 35

5. A device of the class described comprising a swingable platform; a support for said platform; a movable member for engaging said support, and preventing, during such engagement, swinging movement of said platform; movable means for engaging said movable member and normally retaining the same in said engagement, said movable means being provided with a recess for the reception of one end of said movable member upon movement of said movable means to a predetermined position; releasable means for preventing movement of said movable means to said predetermined position; resilient means for moving said movable means to said predetermined position upon release of said preventing means; and resilient means for moving said movable member into engagement with said recess upon movement of said movable means to 50 said predetermined position.

In testimony whereof I have signed the foregoing.

JAMES H. MYRE.
